No. 7,383.

Apr. 21. 1874

UNITED STATES PATENT OFFICE.

CALVIN L. BUTLER, OF GREENFIELD, ASSIGNOR TO THE JOHN RUSSELL CUTLERY COMPANY, OF TURNER'S FALLS, MASSACHUSETTS.

DESIGN FOR CUTLERY-HANDLES.

Specification forming part of Design No. 7,383, dated April 21, 1874; application filed April 4, 1874.
[Term of Patent 7 years.]

B.

To all whom it may concern:

Be it known that I, C. L. BUTLER, of Greenfield, Franklin county, Massachusetts, have invented a Design for Cutlery-Handles, of which the following is a specification:

The nature of my design is fully represented in the accompanying drawing, to which reference is made.

A represents the handle, which is tipped on the end portion B with bright or plated metal, inclosing a rectangular figure, C, on each side of the surface of the handle, traversed length-

wise by a bar, D, with a circular figure, E, of the material forming the tip.

I claim as my invention—

The design for cutlery-handles, consisting of bright or plated metal tips B, inclosing a rectangular figure, C, traversed by the bar D E, substantially in the manner described.

CALVIN L. BUTLER.
